US00D915523S

(12) **United States Design Patent** (10) Patent No.: **US D915,523 S**
(45) Date of Patent: ** *Apr. 6, 2021

(54) **GAMING TERMINAL**

(71) Applicant: **SG Gaming, Inc.**, Las Vegas, NV (US)

(72) Inventors: **Robert J. Glenn, II**, Las Vegas, NV (US); **Paul M. Lesley**, Chicago, IL (US); **Christian L. Castro**, Chicago, IL (US)

(73) Assignee: **SG Gaming, Inc.**, Las Vegas, NV (US)

(*) Notice: This patent is subject to a terminal disclaimer.

(**) Term: **15 Years**

(21) Appl. No.: **29/619,398**

(22) Filed: **Sep. 28, 2017**

(51) LOC (13) Cl. **21-03**

CLAIM

The ornamental design for a gaming terminal, as shown and described.

DESCRIPTION

FIG. 1 is a front perspective view of a gaming terminal showing our new design;

FIG. 2 is a top view thereof;

FIG. 3 is a front perspective view of a second embodiment of a gaming terminal showing our new design;

FIG. 4 is a top view thereof;

FIG. 5 is a front perspective view of a third embodiment of a gaming terminal showing our new design;

FIG. 6 is a top view thereof;

FIG. 7 is a front perspective view of a fourth embodiment of a gaming terminal showing our new design;

FIG. 8 is a top view thereof;

FIG. 9 is a front perspective view of a fifth embodiment of a gaming terminal showing our new design;

FIG. 10 is a top view thereof;

FIG. 11 is a front perspective view of a sixth embodiment of a gaming terminal showing our new design;

FIG. 12 is a top view thereof;

FIG. 13 is a front perspective view of a seventh embodiment of a gaming terminal showing our new design;

FIG. 14 is a top view thereof;

FIG. 15 is a front perspective view of an eighth embodiment of a gaming terminal showing our new design; and,

FIG. 16 is a top view thereof.

The broken line showing of the remainder of the gaming terminal forms no part of the claimed design.

1 Claim, 8 Drawing Sheets
